UNITED STATES PATENT OFFICE.

WILLIAM H. PENDERY, OF LOCKLAND, OHIO, ASSIGNOR TO THE PHILIP CAREY MANUFACTURING COMPANY, OF LOCKLAND, OHIO, A CORPORATION OF OHIO.

READY-MADE ROOFING.

948,116.

Specification of Letters Patent.

Patented Feb. 1, 1910.

Application filed March 29, 1909. Serial No. 436,437.

To all whom it may concern:

Be it known that I, WILLIAM H. PENDERY, a citizen of the United States, residing at Lockland, in the county of Hamilton and State of Ohio, have invented certain new and useful Improvements in Ready-Made Roofing, of which the following is a specification.

My invention relates to roofing material, 10 and its object is to provide a composite roofing in elongated sheets ready to be laid with their parts adjacent to their longer edges overlapping in such a manner as to prevent the entrance of moisture where the 15 sheets overlap and avoid decay of the roofing material and the rusting of the nails which are used to attach it to the roof.

My invention consists in the combination 20 with a main strip of roofing made up of a composition body and a woven strengthening layer imposed thereon and partially embedded therein, and overlapping and folded upon the body, whereby a reinforced nailing section and a covering lap therefor is provided, of an adjunctive strip of like composition 25 upon which an extension of the covering lap is imposed and partially embedded therein to join said adjunctive strip to the main strip and allow it to extend coincident 30 therewith along the edge thereof when the covering lap lies over the reinforced nailing section.

In the drawing: Figure 1 is a general perspective view, showing a strip of roofing of 35 my improved construction. Fig. 2 is a sectional perspective view of part of the same, enlarged, the adjunctive strip and attached covering lap being represented as in raised position as in the process of laying the roofing. Fig. 3 is a cross sectional view, further enlarged, illustrating the overlapping part 40 of the strip laid and nailed but with the adjunctive strip and covering lap yet in raised position. Fig. 4 is a similar cross 45 sectional view, illustrating the finished condition of the roofing, constructed according to my invention. Fig. 5 is a partial cross sectional view, showing the various strata of the roofing strip as they are brought together in constructing the roofing.

The roofing is made up of the body 1, of cement of similar composition, the essential elements of which are viscousness to cause it to adhere to the woven strengthening layer 50 2, and pliability, to form a roofing sheet that

may be conveniently rolled up and handled. The woven strengthening layer is composed of burlap, which at one edge 3 of the sheet terminates coincident with the cement body 1, but at the other edge of the sheet continues past the cement body, being partially embedded in the cement body up to this second mentioned edge, coincident with which it is folded at 4 to lie back on itself, within the proximity of this edge, throughout the length of the sheet. This strengthening layer has another fold at 5 extending parallel with the edge 3 and the fold 4 throughout the length of the sheet, and at a distance from said edge and said fold sufficient to leave a reinforced section 6, having two thicknesses of the strengthening layer, to constitute a nailing section through which the nails 7 are driven into the boards upon which the roofing is laid, and against which nailing section the heads of the nails bear to firmly hold the roofing in place. Past the fold 5, the woven strengthening layer 2 again extends toward the edge 3 and beyond it, where it is partially embedded, in the same manner as it is partially embedded in the body 1 of the sheet, in a cement body 1^a of an adjunctive strip adapted to extend coincident with the main sheet, along the edge thereof, with one of its edges adjacent to and its other edge away from said main sheet, when the roofing is in place in its finished condition. The woven strengthening layer 2 terminates coincident with the edge of the adjunctive strip away from said main sheet. The roofing sheet is completed by adding on the lower side of the cement body a layer 8 of compact material such as paper, this layer coming next to the roof boards 9, into which the nails 7 are driven.

Each roofing sheet is beveled near the edge 3 to decrease the bulkiness of the seam formed by overlapping the sheets, and when the nails have been driven through the nailing section between the folds 4 and 5, the part of the woven strengthening layer between the fold 5 and the adjacent edge of the adjunctive strip is secured down over the heads of the nails and over the nailing section, bringing the lower side of the adjunctive strip against the upper side of the next sheet with which the seam is made, being secured thereto by a suitable cement which is supplied in sufficient quantity to fill up the space between the respective adjacent edges of the main

sheet and the adjunctive strip, also being supplied in sufficient quantity to thoroughly fill up the meshes of the woven strengthening layer 2 where it extends over the nailing section and nails. This cement is, preferably, of material similar to that composing the cement body of the roofing sheet and adjunctive strip, so that a practically continuous covering is thus effected.

10 Preparatory to the construction of the roofing, a seam 10 is run through the part of the strengthening layer 2 between the folds 4 and 5 and through the main part of this strengthening layer closely adjacent and 15 parallel to the fold 5. This seam 10 is advantageous in handling the strengthening layer before it is applied to the cement body during the manufacture of the roofing, and also adds to its strength after the roofing is 20 completed, in that it reinforces the connection of the two parts of the strengthening layer 2 thus connected together, and prevents the distortion of the strengthening layer in this region under the action of winds or 25 other forces, which distortion would be liable to disturb the cement coating over and around the nailing section. As illustrated, I prefer to provide the woven strengthening layer 2, on the one side, and the layer of 30 compact material 8, on the other side, with a coating of suitable weather proofing material 11, these coatings extending on both sides from the edge 3 of the main sheet to the extreme edge of the adjunctive strip.

35 By providing the adjunctive strip of composition identical with or similar to that of the main sheet, and of equal thickness therewith, the roofing sheets, in their completed condition as applied to the roof, have the 40 nails entirely inclosed within the body of the sheet at a distance from the edge of the sheet increased over that at which they are in the ordinary sheet equal to the width of the adjunctive strip. This adjunctive strip, 45 being of the same thickness as the main sheet, dispenses with the necessity of bringing the covering lap down over the edge of the body part of the sheet, thus avoiding all the difficulty caused by the puckering of this covering 50 lap. Thus the roofing may be applied with the exercise of less skill, at a decreased cost, but at the same time, owing to the increased protection afforded in the region of the nailed seam, the entrance of moisture is 55 more effectually prevented, avoiding the decay of the roofing adjacent to the nails and thus adding to the lasting qualities thereof under the conditions imposed by wind and other forces tending to tear the roofing from 60 the roof. While thus having increased advantages in use, the roofing may be very conveniently produced, it only being necessary to provide the woven strengthening layer and the underlying layer of paper, or other 65 material, with a layer of the cement or simi-

lar composition running between them, the strengthening layer being provided, folded, and sewed, as hereinbefore described, and the layer of paper, or similar material, being provided slitted to divide it into the foundations for the main sheet and the adjunctive strip, respectively. These parts, ready to be thus brought together, are best illustrated in Fig. 5 of the drawing. The layer of paper, or similar material, being already slitted, and the layer of strengthening material being pliable, it will be seen that the cement, or similar composition, constituting the body of the roofing, will readily separate coincident with the slit in the paper foundation so that it is only necessary to run the layers or strata together, in the usual manner, in manufacturing my improved roofing, after which the adjunctive strip may be readily separated, except for the strengthening layer which binds it to the main sheet ready for use. The seam running along adjacent to the fold 5 affords a fulcrum for accomplishing the separation of the covering lap from the nailing section to permit the nails to be driven through said nailing section in applying the roofing. The weather proofing is applied to both sides of the roofing after the strata have been brought together, and is also caused to cover the inner adjacent edges of the main sheet and adjunctive strip, respectively, as well as their outer edges.

Having fully described my invention, what I claim as new and desire to secure by Letters Patent is:

1. In ready made roofing, the combination with a main strip of roofing having a nailing section adjacent to one edge, and a covering lap therefor, of an adjunctive strip attached to the main strip by means of said covering lap and adapted to extend coincident with the main strip along the edge thereof when the covering lap lies over the nailing section.

2. In ready made roofing, the combination with a main strip of roofing made up of a composition body and a woven strengthening layer imposed thereon and partially embedded therein, and overlapping and folded upon the body, whereby a reinforced nailing section and a covering lap therefor is provided, of an adjunctive strip of like composition upon which an extension of the covering lap is imposed and partially embedded therein to join said adjunctive strip to the main strip and allow it to extend coincident therewith along the edge thereof when the covering lap lies over the reinforced nailing section.

3. In ready made roofing, the combination with a main strip of roofing made up of a composition body and a woven strengthening layer imposed thereon and partially embedded therein, overlapping and folded upon the body and having a seam attaching

the folded part of said strengthening layer to the main part thereof, whereby a double thickness of said strengthening layer is provided to constitute a nailing section and the 5 strengthening layer past the seam forming a covering lap for the nailing section, of an adjunctive strip comprising a composition body upon which an extension of the covering lap is imposed and partially embedded therein to join said adjunctive strip to the main strip and allow it to extend coincident therewith along the edge thereof when the covering lap lies over the reinforced nailing section, said seam affording a 10 fulcrum for accomplishing the separation of the covering lap from the nailing section after the strengthening layer is embedded in the composition body.

4. In ready made roofing, the combination 20 with a composition body and a woven strengthening layer imposed thereon and partially embedded therein, and overlapping and folded upon the body adjacent to one edge throughout the length of 25 the roofing, whereby a reinforced nailing section and a covering lap therefor is provided, of a foundation of compact material imposed upon the composition body on the side opposite from that in which the 30 strengthening layer is embedded, said foundation being provided with a slit running longitudinally of the roofing in the region adjacent to the edge adjacent to which the strengthening layer overlaps and is folded 35 upon the body, whereby said roofing may be divided into a main strip and an adjunctive strip of like composition, with an extension of the covering lap of the strengthening layer joining the adjunctive strip to the 40 main strip, substantially as set forth.

5. In ready made roofing, the combination 45 of a composition body and a strengthening layer imposed thereon and partially embedded therein, and overlapping and folded upon the body adjacent to one edge throughout the length of the roofing, and having a seam running longitudinally of the roofing to secure the overlapped and folded part of the strengthening layer to its 50 main part, whereby the extension of the strengthening layer past the seam constitutes a covering lap, and a foundation of compact material imposed upon the compo-

sition body on the side opposite to that in which the strengthening layer is partially 55 embedded therein, having a slit running longitudinally of the roofing adjacent to the edge adjacent to which the strengthening layer overlaps and is folded upon the body, whereby the roofing may be divided 60 into a main strip and an adjunctive strip of like composition, with the adjunctive strip joined to the main strip by an extension of the covering lap and whereby the covering lap with the adjunctive strip joined 65 thereby may be raised from the body, the section of the body under the covering lap constituting a nailing section, substantially as set forth.

6. In ready made roofing, the combination 70 of a composition body and a woven strengthening layer and a foundation of compact material, the composition body running between the strengthening layer and the foundation, of a slit running longitudinally in the foundation of compact material near one edge of the roofing, the woven strengthening layer being folded to be raised from the composition body, and said slit 75 dividing the roofing into a main strip and an adjunctive strip joined together by the strengthening layer, substantially as set forth.

7. In ready made roofing, the combination 80 of a composition body and a woven strengthening layer imposed thereon and partially embedded therein and folded upon itself to constitute a reinforced nailing section and a covering lap on said roofing, and a foundation of compact material imposed 85 upon the composition body on the side opposite to that in which the strengthening layer is partially embedded, said strengthening layer and foundation of compact material terminating coincident with the edge of the 90 composition body, and the foundation being provided with a slit extending longitudinally of the roofing near one edge, whereby the roofing is divided into a main strip and an adjunctive strip joined together by the 95 strengthening layer, substantially as set forth.
